UNITED STATES PATENT OFFICE

JOHN GLOVER, OF CHICAGO, ILLINOIS

DESIGN FOR AN INSECT REPELLENT

Application filed July 18, 1929. Serial No. 32,107. Term of patent 14 years.

To all whom it may concern:

Be it known that I, JOHN GLOVER, a citizen of the United States, residing in Chicago, Cook County, Illinois, have invented a new, original, and ornamental Design for an Insect Repellent, of which the following is a specification, reference being had to the accompanying drawings, forming part hereof.

Figures 1 and 3 of the drawings show respectively obverse and reverse sides of the cake, and Figs. 2 and 4 are respective side and front end elevations of the article.

I claim:

The ornamental design for an insect repellent, substantially as shown.

JOHN GLOVER.
